(57) **CLAIM**

I claim the ornamental design for a faceted nasal seal with bottom rim, substantially as shown and described.

DESCRIPTION

FIG. 1 is a front isometric view from the bottom left of a faceted nasal seal with bottom rim.

FIG. 2 is a front isometric view of the faceted nasal seal with bottom rim of FIG. 1.

FIG. 3 is a top plan view of the faceted nasal seal with bottom rim of FIG. 1.

FIG. 4 is a side elevation view of the faceted nasal seal with bottom rim of FIG. 1.

FIG. 5 is a bottom plan view of the faceted nasal seal with bottom rim of FIG. 1.

FIG. 6 is a side elevation view in cross section taken along the line 6-6 in FIG. 5 of the faceted nasal seal with bottom rim of FIG. 1; and,

FIG. 7 is a bottom isometric view of the faceted nasal seal with bottom rim of FIG. 1.

The broken lines shown in the drawings are for purposes of illustrating use and environment only and form no part of the claimed design.
